RADIO ANTENNA

Andrew Massey and Henry Hulick, Raleigh, N. C.

Application August 9, 1934, Serial No. 739,086

4 Claims. (Cl. 250—11)

This invention relates to improvements in radio antennæ and has particular reference to an apparatus for reflecting radio frequency energy from an emitter in all directions parallel to the surface of the earth.

In the sending out of radio frequency energy by the conventional form of antenna, much of the energy emitted travels in a skyward direction and is of practically no use in commercial radio broadcasting. The main object of this invention is to reflect the radiation of the radio frequency energy from the emitter in such direction as to travel parallel to, and at a constant distance above the earth's surface. This method of transmission eliminates all angular radiation and converts all the transmitted energy into ground wave where it will create a most satisfactory service area with minimum interference at a distance.

Another feature of the invention resides in a radio antenna which includes a cupped emitter, a parabolic reflector, and a conical diverter, all arranged with their geometrical center lines in the same vertical plane.

With these and other objects in view, the invention resides in the novel combination and arrangement of parts, the essential features of which are hereinafter described in the following specification, are particularly pointed out in the appended claims and are illustrated in the accompanying drawing, in which:

Figure 1 is a diagrammatic view illustrating the invention partly in side elevation and partly in section.

Figure 2 is a view similar to Figure 1, but showing the parts in reversed position.

Referring to the drawing by reference characters, the numeral 10 designates a conical diverter, the outer deflecting inclined surfaces 11 of which are of a 45 degree angle and of any suitable metal such as steel, copper, or aluminum. In Figure 1 of the drawing, the flat base 12 of the diverter is shown as resting upon the earth's surface A and the apex points skyward.

Supported above the top or apex of the conical diverter and in vertical axial alinement therewith is a hemispherical shaped baffle and reflector 13, the walls of which are concavo-convex with the open side thereof facing away from the conical diverter.

Supported above the baffle 13 is a paraboloid reflector 14, the axis of which is in vertical alinement with the vertical axis of the diverter 10 and baffle 13 while the circumference of the same is the same or approximately the same as the base 12 of the diverter 10. The reflector 14 is con-

structed of any suitable metal such as steel, copper or aluminum and is concavo-convex with the concave side facing the conical diverter 10. The peripheral edge of the parabolical reflector 14 is on the same plane as the circumferential edge of the hemispherical baffle 13 for a purpose to be presently explained.

Mounted centrally of the hemispherical shaped baffle 13 is a radio frequency energy radiator or emitter 15, which may be in the form of a solenoid with the windings of the coils extending equal distances from opposite sides of the axial center of the hemispherical baffle 13.

From the description thus far, it will be understood that the diverter 10, hemispherical reflector 13, parabolic reflector 14, and emitter 15 are arranged in vertical axial alinement with the baffle interposed between the diverter and the parabolic reflector, while the emitter is cupped on the diverter side by the hemispherical baffle 13.

In practice, the radio frequency energy discharged by the radiator or emitter 15 is transmitted radially, the baffle 13 preventing the direct transmission of the energy to the conical diverter, and reflecting them upwardly toward the parabolic reflector 14, it being noted that the baffle is relatively small in diameter in comparison with the diameter of the parabolic reflector 14 and the base of conical diverter 10. The outwardly and upwardly diverted radio frequency energy shown by the lines 16 directly strike the curved reflecting surfaces of the parabolic reflector at an angle and are reflected with those transmitted from the reflector 13 in a downward vertical direction shown by the lines 17 into the path of the upwardly converging walls 11 of the conical diverter 10. After striking the upwardly inclined walls of the diverter, the radio frequency energy is diverted or reflected at an angle of 90 degrees from the vertical lines 17, or in a horizontal plane parallel to the earth's surface A as indicated by the lines 18. Thus it will be seen that the radio frequency energy from the emitter 15 is first transmitted to the parabolic reflector 14, thence downwardly upon the diverter 10, and is reflected from the diverter 10 in a direction to travel parallel to and at a constant distance above the earth's surface. This eliminates all angular radiation and converts all the transmitted radio frequency energy into ground wave

where it will create a most satisfactory service area with minimum interference at a distance.

In Figure 1 of the drawing, we have illustrated the apparatus with the base 12 of the cone resting upon the earth's surface and the other parts

supported thereabove. However, the entire structure may be reversed 180 degrees, as shown in Figure 2, so that the convex side of the parabolic reflector rests upon the earth's surface while the 5 base of the conical diverter is at the top. The same result is obtained so far as the transmission of the radio frequency energy is concerned, but the direction of reflection from the emitter 15 and reflector 13 is downwardly while the reflection 10 from the parabolic reflector is upwardly onto the elevated conical diverter 10. In this position the ground waves are transmitted on a higher level than that shown in Figure 1.

While we have shown and described what we 15 consider to be the preferred embodiment of our invention, it will be appreciated that the parts have been shown more or less diagrammatic and we do not wish to restrict ourselves to various 20 specific details of construction, but that such alterations and changes as come within the scope 25 of the appended claims may be resorted to if desired.

Having thus described the invention, what we 25 claim as new and desire to secure by Letters Patent of the United States, is:—

1. A radio antenna comprising in combination, 30 a conical diverter, a parabolic reflector, said conical diverter and parabolic reflector being arranged in superimposed relation and with their center axes in vertical alinement, a radio frequency 35 emitter interposed between said conical diverter and said parabolic reflector, and a hemispherical baffle interposed between the cone diverter and the reflector, said baffle and reflector having their concaved faces opposed and positioned with their peripheral edges on a horizontal plane whereby to concentrate all of the energy from said emitter upon said parabolic reflector from where it is reflected upon the inclined 40 sides of said conical diverter and deflected radially and horizontally therefrom.

2. A radio antenna comprising in combination, 45 a conical diverter arranged with its axial center disposed vertical, a parabolic reflector spaced from the small end of said conical diverter, a hemispherical shaped reflector interposed be-

tween said conical diverter and said parabolic reflector, and a radio frequency emitter enclosed by said parabolic reflector and said hemispherical reflector, said reflectors having their concaved faces opposed and positioned with respect 5 to each other so as to prevent direct radiation of waves from the emitter without striking either of said reflectors and both of the reflectors and said emitter being in vertical axial alinement with the axis of said conical diverter, whereby the 10 energy emitted from said emitter is reflected in a vertical direction by said parabolic reflector onto the inclined surfaces of said conical diverter, and deflected radially and horizontally therefrom parallel to the earth's surface. 15

3. A radio antenna comprising in combination, 20 a conical diverter, a parabolic reflector, a relatively small hemispherical baffle interposed between said conical diverter and said parabolic reflector and a radio frequency emitter positioned 25 axially with respect to the baffle, said conical diverter, parabolic reflector and baffle being arranged in vertical axial alinement, said baffle and parabolic reflector having their peripheral edges on a horizontal plane to prevent radiation 30 of waves from the emitter without striking either the baffle or the reflector and said baffle and reflector further being arranged with their concaved faces opposed so as to concentrate all of the waves from the emitter against the inclined 35 walls of the conical diverter for deflection radially and horizontally therefrom.

4. A radio antenna comprising in combination, 40 a conical diverter, a parabolic reflector, a relatively small hemispherical baffle interposed between said conical diverter and said parabolic reflector, and a radio frequency emitter positioned axially with respect to the baffle, said 45 conical diverter, parabolic reflector and baffle being arranged in vertical axial alinement, and said baffle and parabolic reflector having their peripheral edges on a horizontal plane so as to prevent radiation of waves from the emitter without striking either the baffle or the reflector.
